(57) **CLAIM**

The ornamental design for a jewelry container, as shown and described.

DESCRIPTION

FIG. 1 is a top plan view of a jewelry container showing my new design, with the container shown closed;

FIG. 2 is a right side view thereof;

FIG. 3 is a left side view thereof;

FIG. 4 is a rear elevational view thereof;

FIG. 5 is a front elevational view thereof;

FIG. 6 is a top plan view thereof similar to that of FIG. 1, with the container shown open and showing an ornamental insert therein; and,

FIG. 7 is a right side view according to FIG. 6, the left side view being substantially identical thereto, reversed.

The broken line portions of the disclosure are for illustrative purposes only and form no part of the claimed design.
